CONTROLLED FREQUENCY OSCILLATOR

Raymond P. Mork, Schenectady, N. Y., assignor
to General Electric Company, a corporation of
New York

Application January 26, 1945, Serial No. 574,658

11 Claims. (Cl. 250—36)

1

My invention relates to controlled frequency oscillators, and more particularly to apparatus for modulating the frequency of oscillations in accordance with the intensity of a desired signal or a quantity being measured or recorded.

My invention is particularly applicable to measuring and recording apparatus where it is desired to control the frequency of electric oscillations in accordance with a condition, such as temperature, humidity, pressure, liquid level, mechanical stress, or the like. The oscillations thus controlled may be recorded, as by a magnetic wire recorder or the like. In such apparatus, it is convenient to provide an oscillator having a frequency which is a function of the impedance of a variable measuring impedance. More particularly, it is desirable to provide an oscillator, the output frequency of which is a function of a small resistance change. Such an oscillator should be compensated for resistance changes in the measuring resistor resulting from changes in ambient temperature, and should provide a large frequency swing in response to small percentage changes in the resistance of the measuring resistor.

Accordingly, it is an object of my invention to provide a new and improved ambient temperature compensated oscillator the output frequency of which is variable over a relatively wide range in response to a small percentage change in the value of one of the circuit impedance elements.

It is a still further object of my invention to provide a new and improved electric oscillation generator having a frequency determined by a phase displacement of electric oscillations.

It is a further object of my invention to provide a new and improved oscillation generator having a natural frequency determined by the phase displacement between oscillations at the input and output terminals of a phase shifting circuit interposed in the feedback path of the oscillator.

It is still another object of my invention to provide a new and improved arrangement for shifting the phase of electric oscillations.

My invention itself will be more fully understood and its objects and advantages further appreciated by referring now to the following detailed specification taken in conjunction with the accompanying drawing in which Fig. 1 is a schematic circuit diagram of a frequency controlled oscillator embodying my invention; and Figs. 2 and 3 are vector diagrams illustrating the operating of certain phase shifting circuits forming part of the invention.

Referring now to the drawing, and particu-

2

larly to Fig. 1, I have shown an oscillation generator comprising an amplifier 1 and a pair of phase shifting networks or circuits 2 and 3. The amplifier 1 comprises a pair of electric discharge devices 4 and 5 connected in cascade relation between an input circuit coupled to the circuit 3 and an output circuit including a transformer 7. The discharge device 4 comprises a cathode 8, a control electrode 9, screen and suppressor grids 10 and 11, respectively, and an anode 12. The screen grid 10 is connected through a resistor 13 to a suitable source of positive potential indicated upon the drawing as B+, and the suppressor grid 11 is connected directly to the cathode 8. The anode 12 is connected to the positive potential source B+ through a load resistor 14. The negative end of the load resistor is connected through a coupling condenser 15 to the input electrode of the amplifying discharge device 5. Suitable grid bias for the discharge device 4 is provided by a cathode bias resistor 16 connected between the cathode 8 and ground in parallel with a by-pass condenser 16'. The amplifier 5 includes a cathode 17, a control electrode 18 connected to the coupling capacitor 15 and a grid resistor 15', screen and suppressor grids 19 and 20, respectively, and an anode 21. The screen grid 19 is connected through a resistor 22 to the positive potential source B+, and the suppressor grid 20 is connected directly to the cathode 17. The anode 21 is connected through the primary winding 23 of the transformer 7 to the positive potential source B+.

Suitable grid bias for the discharge device 5 is supplied by a cathode resistor 24 connected between the cathode 17 and ground in parallel with a by-pass condenser 24'.

The secondary winding 25 of the transformer 7 is connected to supply energy from the output circuit of the amplifier 1 back to the amplifier input circuit through the phase shifting circuits 2 and 3 in such phase and with such gain as to support oscillations. In practice, I have found

that it is preferable in a circuit constructed in accordance with my invention to provide an overall gain through the circuits 1, 2 and 3, not appreciably greater than unity. It may be here noted that the amplifier 1 is constructed in such a manner that the phase shift between oscillations at the input and output circuits of the amplifier is substantially constant over the frequency range used. Ordinarily, and preferably, this phase shift is either substantially zero or 180 electrical degrees, depending upon the manner in

which the output transformer secondary winding 25 is connected to the feedback circuit.

The phase shifting network 2 is supplied with oscillations from the secondary winding 25 of the transformer 7 and comprises a resistance bridge having input terminals 26 and output terminals 27. The resistance bridge comprises two serially connected pairs of resistors 28, 29 and 30, 31 connected in parallel circuit relation between the input terminals 26, the output terminals 27 of the bridge being between the resistors 28 and 29 and between the resistors 30 and 31. The resistor 31 is variable in accordance with the value of an impressed signal or a measured condition, and determines by its resistance the frequency of oscillation of the oscillator. By way of example, it may be assumed that the variable resistor 31 is the variable resistance element of a resistance strain gage 32 connected continuously to measure the stress in a structural member. It will be understood that when the resistance bridge is balanced the ratio of the resistances of the resistors 29 and 31 is equal to the ratio of the resistances of the resistors 28 and 30 and preferably equal to unity. Under such balanced condition, no voltage component arising from the bridge circuit alone appears at the output terminals 27. On the other hand, if the bridge is unbalanced by change in the resistance of the gage resistor 31, a voltage component arising from bridge unbalance and in phase with the voltage applied to the input terminals of the resistance bridge appears at the output terminals 27.

In order to shift the phase of oscillations at the bridge output terminals 27 with respect to oscillations supplied to the input terminals 26, I connect across the resistor 30 a capacitor 33 of small capacitance thereby to provide an impedance large relative to the impedance of the gage resistance 31. By thus connecting the capacitor 33 and the gage resistor 31 in series circuit relation between the bridge input terminals 26, there is superposed upon the resistor 31 a differentiated voltage component in substantially quadrature relation with the oscillations supplied to the input terminals 26. This quadrature voltage component combines with the in-phase output voltage component due to bridge unbalance alone to provide at the output terminals 27 oscillations shifted in phase relative to oscillations supplied to the input terminals 26.

For a more complete understanding of the operation of the phase shifting circuit 2, reference may now be had to Fig. 2 wherein is illustrated vectorially the phase relation between various current and voltage components existing in the circuit 2. At Fig. 2, the vector E_{25} represents the voltage applied to the input terminals 26 of the circuit 2. Since the impedance of the condenser 33 is large compared to the impedance of the gage resistor 31, the current through the series circuit comprising the condenser 33 and resistor 31 may be represented by a vector I_{33} leading the voltage E_{25} by substantially 90 electrical degrees. A voltage vector E_{31C} represents the voltage drop through the resistor 31 due to the condenser current I_{33} . In addition to the condenser current through the resistor 31, currents in phase with the applied voltage E_{25} flow through the parallel resistor paths 28, 29 and 30, 31 and produce across the resistors 29 and 31 voltage vectors E_{29B} and E_{31B} . It will be understood that when the voltages E_{29B} and E_{31B} are unequal, as shown, the bridge is in a state of unbalance.

These voltage vectors are in phase with the applied voltage E_{25} .

It will now be evident that the output voltage appearing at the bridge terminals 27 is the sum of the voltage vectors E_{29B} , E_{31B} and E_{31C} . Since the voltage vectors E_{29B} and E_{31B} are in opposite phase relation with respect to the output terminals 27, their difference represents the voltage component at the terminals 27 due to bridge unbalance alone. It will be understood that this differential voltage $E_{31B} - E_{29B}$ may vary between zero and a maximum value determined by the maximum percentage change of resistance of the resistor 31, and may be either positive or negative depending upon the direction of the resistance change. Thus, the net output voltage E_{27} being the vectorial sum of $E_{31B} - E_{29B}$ and E_{31C} , at Fig. 2 is variable in phase from a position in phase with the voltage E_{31C} when the bridge is balanced to positions of maximum phase displacement in either direction. The output voltage E_{27} from circuit 2 leads the input voltage E_{25} by an angle θ_1 . At maximum bridge unbalance, the displacement angle θ_1 is a minimum, and I have found that, in practice, it is desirable to limit the minimum phase displacement θ_1 to approximately the angle shown at Fig. 2 wherein the magnitude of the voltage vector E_{31C} is approximately twice the magnitude of the differential voltage vector $E_{31B} - E_{29B}$ due to maximum bridge unbalance.

From the foregoing, it will be understood that the phase angle θ_1 is variable over a wide range in response to small percentage resistance changes 35 of the resistor 31. This property arises from the fact that, due to the bridge circuit arrangement, only a small percentage change of the resistor 31 is necessary to produce an appreciable differential voltage due to bridge unbalance, while the 40 small percentage resistance change has little effect upon the magnitude of the voltage component E_{31C} . Furthermore, the phase shifting circuit 2 is compensated for ambient temperature changes by reason of the voltage balancing effect of the bridge circuit forming a part thereof. Preferably ambient temperature compensation is effected by utilizing pairs of resistors 28 and 30 and 29 and 31 of similar characteristics.

The output voltage E_{27} from the phase shifting network 2 is impressed upon the phase shifting network 3 which comprises a pair of resistance-capacitance phase shifting circuits connected in cascade relation. Specifically, the circuit 3 comprises a resistor 34 and a capacitor 35 connected in series circuit relation across the output terminals 27 of the circuit 2 and a resistor 36 and capacitor 37 connected in series circuit relation across the capacitor 35. An output voltage from the circuit 3 taken off across the capacitor 37 is supplied to the control electrode 9 of the amplifying discharge device 4.

The circuit 3 shifts the phase of oscillation supplied to it in a sense opposite to that in which the circuit 2 shifts the phase of applied oscillations, and the amount of phase shift produced by the circuit 3 is dependent upon the frequency of oscillations supplied thereto. Thus, when the circuit constants of the circuit 3 are properly proportioned and a predetermined frequency is supplied to the circuit 3, the output voltage from the circuit 3 will be in phase with the input voltage to the circuit 2.

The manner in which phase shifting takes place in the circuit 3 will be more evident by inspection of Fig. 3. At Fig. 3, I have shown the

input voltage to the circuit 3 as the vector E_{27} of Fig. 2. In the circuit 3, the capacitors 35 and 37 are small, so that their impedances are of the same order of magnitude as the impedances of the resistors 34 and 36, respectively. Accordingly, therefore, the current through the capacitor 35 may be represented by a vector I_{35} leading the vector E_{27} by an angle ϕ_1 of less than 90 electrical degrees. The voltage drop across the capacitor 35 produced by the current I_{35} is illustrated by a vector E_{35} lagging the current vector I_{35} by 90 electrical degrees. The voltage E_{35} is that supplied to the second stage of the phase shifting circuit 3 and, due to this voltage, a current I_{37} passes through the condenser 37. The current I_{37} leads the voltage E_{35} by an angle ϕ_2 equal approximately to ϕ_1 . The voltage drop across the condenser 37 lags the current I_{37} by 90 electrical degrees and is shown at Fig. 2 as a vector E_{37} . It will now be observed that the output voltage E_{37} lags the input voltage E_{27} by an angle θ_2 and is in phase with the voltage E_{25} supplied to the input of the phase shifting circuit 2. Accordingly, therefore, at the frequency assumed, the phase angle θ_1 of Fig. 2 is equal to the phase angle θ_2 of Fig. 3. It will be evident that the angle θ_2 is determined by the angles ϕ_1 and ϕ_2 . It is well understood by those skilled in the art that the phase angles ϕ_1 and ϕ_2 are determined by the frequency of the oscillations supplied to the phase shifting circuit 3. Accordingly, therefore, the angle θ_2 is determined by the frequency of the supplied oscillations.

Where large frequency deviations are encountered, it will be found desirable to provide manual or automatic amplifier gain control means.

In view of the foregoing explanation, the operation of my new and improved oscillator will be fully understood from the following brief description. As described hereinbefore, the angle of phase displacement θ_1 between the input and output oscillations at the circuit 2 is determined primarily by the resistance of the bridge element 31 and is substantially independent of the frequency oscillations applied to the circuit 2, while the angle of displacement θ_2 between the input and output oscillations at the circuit 3 is determined primarily by the frequency of oscillations applied to the circuit 3. The phase shifting circuits 2 and 3 are connected in cascade circuit relation between the output and input circuits of the amplifier 1. I have found that an amplifier provided with sufficient feedback through a pair of phase shifting circuits of the type described will oscillate at a natural frequency such as the total phase shift through the amplifier and feedback network is a minimum. Specifically, where the phase shifting circuits shift the phase of the regenerative oscillations in opposite senses, the natural frequency of oscillation will be that at which the net phase shift, including the small but relatively constant amplifier phase shift, is zero, for, at this frequency, the energy supplied through the feedback circuit is a maximum.

It will now be understood that, with the resistance bridge of the phase shifting circuit 2 balanced, the circuit 2 produces a 90° phase displacement. Accordingly, therefore, the mean or center frequency of oscillations will be that at which the phase shift through the circuit 3 is plus or minus 90°, depending upon the orientation of the transformer 7. As the bridge circuit is unbalanced in one direction or the other by change of resistance of the resistor 31, the circuit 2 will effect a phase displacement of the

oscillations supplied to it and, for each each value of phase displacement thus produced, a corresponding natural frequency of oscillations will exist at which the opposite phase displacement effective in the circuit 3 is equal in magnitude. Accordingly, therefore, the frequency of oscillations will be found to be a function of the resistance of the resistor 31.

While I have described, by way of illustration, only a preferred embodiment of my invention, many modifications will occur to those skilled in the art and I, therefore, wish to have it understood that I intend in the appended claims to cover all such modifications as fall within the true spirit and scope of my invention.

What I claim as new and desire to secure by Letters Patent of the United States is:

1. A frequency controlled oscillator comprising an electron discharge amplifier having input and output circuits, and means for supplying oscillations from said output to said input circuit comprising a network for shifting the phase of oscillations by an amount determined by the frequency of said oscillations and a second network for shifting the phase of said oscillations by a selectable amount substantially independent of said frequency.

2. A frequency controlled oscillator comprising an electron discharge amplifier having input and output circuits, and means for supplying oscillations from said output to said input circuits comprising a network for shifting the phase of said oscillations in one sense by an amount determined by the frequency of said oscillations and a second network for shifting the phase of said oscillations in an opposite sense by a selectable amount substantially independent of said frequency.

3. A frequency controlled oscillator comprising an electron discharge amplifier having input and output circuits, said amplifier exhibiting a constant shift in phase between said input and output circuits, and means for supplying oscillations from said output to said input circuits comprising a network for shifting the phase of said oscillations in one sense by a selectable amount substantially independent of the frequency of said oscillations, said phase shifting network including a variable impedance element, and a second network for shifting the phase of said oscillations in an opposite sense by an equal amount, said second phase shifting network being responsive to the frequency of said oscillations and determining said frequency such that the net phase shift between said output and input circuits externally of said amplifier is substantially zero.

4. An oscillation generator comprising an electron discharge device having input and output circuits, a network including a variable resistor for shifting the phase of oscillations derived from said output circuit by an amount dependent upon the resistance of said resistor, and a second phase shifting network responsive to the frequency of oscillations from said first phase shifting network for supplying oscillations to said input circuit substantially in phase with said derived oscillations.

5. An oscillation generator comprising an electron discharge device having input and output circuits, and means for supplying oscillations from said output to said input circuit including, a network substantially independent of the frequency of said oscillations for shifting in one sense the phase of oscillations derived from said output circuit by a selectable amount, a second network for shifting the phase of said oscillations

in an opposite sense by an amount determined by the frequency of said oscillations, and means for supplying to said input circuit oscillations derived from said phase shifting means.

6. An oscillation generator comprising an electron discharge device having input and output circuits, a network for shifting the phase of oscillations derived from said output circuit in one sense by an amount substantially independent of the frequency of said oscillations and dependent upon the value of a variable impedance element of said network, and a second network connected in cascade relation with said first network to shift the phase of said oscillations by an equal amount in an opposite sense, said second network being responsive to the frequency of said oscillations thereby to determine said frequency.

7. An oscillation generator comprising an electron discharge amplifier having input and output circuits, means including an impedance bridge for shifting the phase of oscillations from said output circuit in one sense by an amount substantially independent of the frequency of said oscillations, said impedance bridge including a variable impedance element determining said amount, and means connected in series circuit relation with said first shifting means for shifting the phase of said oscillations by an equal amount in an opposite sense, said second phase shifting means being responsive to the frequency of said oscillations thereby to determine said frequency.

8. An oscillation generator comprising an electron discharge amplifier having input and output circuits, said amplifier providing a substantially fixed phase shift between oscillations supplied to said input circuit and oscillations supplied from said output circuit, a network for shifting the phase of oscillations derived from said output circuit in one sense by a variable amount substantially independent of the frequency of said oscillations, a second network connected in cascade relation with said first network for shifting the phase of said oscillations by an approximately equal amount in an opposite sense, said second network being responsive to the frequency of said oscillations, and means for supplying to said input circuit oscillations derived from said second network.

9. An oscillation generator comprising an electron discharge amplifier having input and output circuits, said amplifier providing between oscillations supplied to said input circuit and oscillations supplied from said output circuit a phase displacement equal to an integral multiple including zero of one hundred and eighty electrical degrees, and means for supplying oscillations from said output circuit to said input circuit including a network substantially independent of the frequency of said oscillations for shifting the phase of said oscillations in one sense by an amount determined by a variable impedance element of said network and a second network responsive to the frequency of said oscillations for shifting the phase of said oscillations an equal amount in the opposite sense, said amplifier and phase shifting networks providing an overall gain of substantially unity.

5 10 15 20 25 30

10. A frequency controlled oscillator comprising an electron discharge device having input and output circuits, phase shifting means for displacing the phase of oscillations derived from said output circuit by a predetermined selectable amount, and means including a frequency responsive phase shifting network utilizing said phase displacement to determine the frequency of said oscillations.

11. A frequency controlled oscillator comprising an electron discharge device having input and output circuits, first phase shifting means for displacing in one sense and by a predetermined selectable amount, the phase of oscillations derived from said output circuit, and means for utilizing said phase displacement to determine the frequency of said oscillations including a network arranged to shift the phase of said oscillations in an opposite sense by an amount dependent upon the frequency of said oscillations.
